BEVERAGE CAFETERIA COUNTER

Murray A. Perl, New London, Frank Laspaluto, Waterford, and Robert J. Sevieri, Old Lyme, Conn., assignors to Facilities Design Associates, Inc., New London, Conn.

Filed Sept. 4, 1969, Ser. No. 19,012

Term of patent 14 years

Int. Cl. D6—01

U.S. Cl. D80—2

Fig. 1

Fig. 2

Fig. 3

Fig. 4

FIG. 1 is a top plan view of a beverage cafeteria counter showing our new design;

FIG. 2 is a side elevational view thereof, the opposite side being the same as the side shown.

FIG. 3 is a rear elevational view thereof; and

FIG. 4 is a front elevational view thereof.

We claim:

The ornamental design for a beverage cafeteria counter, substantially as shown and described.
